UNITED STATES PATENT OFFICE.

CHARLES A. HOGUE, OF HUNTINGBURG, INDIANA.

DESIGN FOR FINGER RING.

Application filed June 15, 1923. Serial No. 6,504. Term of patent 14 years.

To all whom it may concern:

Be it known that I, CHARLES A. HOGUE, a citizen of the United States of America, residing at Huntingburg, in the county of Dubois and State of Indiana, have invented a new, original, and ornamental Design for Finger Ring, of which the following is a specification, reference being had to the ac-

companying drawings, forming a part hereof.

The figure is a perspective view showing my new design.

I claim:

The ornamental design for finger ring as shown.

CHARLES A. HOGUE.
